UNITED STATES PATENT OFFICE.

FRANKLIN DAVID CUMMER, OF CLEVELAND, OHIO; WILLIAM M. CUMMER, ADMINISTRATOR OF SAID FRANKLIN DAVID CUMMER, DECEASED, AS-SIGNOR TO THE F. D. CUMMER & SON COMPANY, OF SAME PLACE.

MECHANICAL DRIER.

SPECIFICATION forming part of Letters Patent No. 634,199, dated October 3, 1899.

Application filed March 25, 1898. Serial No. 675,123. (No model.)

To all whom it may concern:

Be it known that I, FRANKLIN DAVID CUMMER, a citizen of the United States, and a resident of Cleveland, in the county of Cuyahoga and State of Ohio, have invented certain new and useful Improvements in Mechanical Driers, of which the following is a specification.

My invention relates to mechanical driers; and the object of the invention is to supply a machine in which a great variety of materials carrying more or less moisture may be dried on a larger scale—such materials, for example, as city garbage, liquid cement slurry, floated or washed clays, ochers, umbers, and the like, in which much the larger percentage of the material may be in a liquid state and the solids a comparatively small per cent.

In the accompanying drawings, Figure 1 is a plain elevation of my improved drying apparatus. Fig. 2 is a front elevation thereof, looking inward from the left of Fig. 1. Fig. 3 is a plan view of the apparatus seen in Figs. 1 and 2. Fig. 4, Sheet 2, is an elevation of the screen and the distributing passages or channels therefrom. Fig. 5 is a plan view, and Fig. 6 is a longitudinal sectional elevation, of the granulating or distributing mechanism shown in Fig. 1 beneath the screen.

The purpose and plan of the machine shown in the several views are to pass the material through the drying-cylinder, and thus dry the same more or less completely, and then passing this dried and partially-dried material from the cylinder through a screen or separator of some suitable kind to sift out the dry portions thereof, and after subjecting the insufficiently-dried portion of the material to the operations of a granulator or reducer to break it up into small particles when necessary and carry the same along to be passed again through the drying-cylinder, but with the raw material, whatever it may be.

Having reference now to the drawings, the drying-cylinder A is shown in dotted lines, and may be any one of my improved cylinders adapted to do the work, and, as is well known, in these cylinders the dried material

is fed thereto through the breeching B at the front, which also forms an exit for the products of combustion or drying agent or gases and vapor, and the dried or partially-dried material is discharged from the rear end of the cylinder. It is also well known as to my cylinders that the drying agent may enter both through the side and rear end of the cylinder or wholly through the rear end or side, as may be found best, and that the material travels rearward and the drying agent forward through the cylinder.

Now I have found that in the handling of a number of different materials there are reasons why it is not desirable or indeed practicable to so completely dry all the material in a single passage through the machine as to make it what may be termed "commercially" dry. Take, for example, city garbage. I have found by experience that to dry this material by sending it once alone through the drier I not only incur very great danger from explosions, but that a very offensive dust is unavoidably carried with the products of combustion out into the atmosphere, as well as a considerable loss sustained in the more volatile fertilizing properties, which likewise are carried off into the air. Other reasons exist in connection with other materials for not drying to a finish in the first passage through the machine, and in all these materials there is the further consideration of economy, by which I am enabled to utilize the full volume of heat from the furnace without waste or loss to do the greatest amount of drying that can be done with a given quantity of heat furnished. These and other considerations have rendered necessary the present invention to complete my drying system. I have therefore provided means for screening or sifting the product as it comes from the machine, consisting in this instance of the rotary screen C, to which the material is carried by the drag-conveyer D, and the discharge-spout d at the rear end of the machine delivering the material to the said conveyer. From this conveyer the material is discharged into the revolving screen C through spout d'. The screen C is so con-

structed and arranged that it receives the material at one end and discharges it at the other. Beneath the screen is a hopper C', from which lead three several spouts c, c', 5 and c², and at the discharge end of the screen there is a discharge-spout c³ to receive the material which does not sift through and which with the spout c empties directly into the upper granulator-section having casing G. 10 The spout c' is supposed to receive the bulk of the dried material sifted through screen C into hopper C', whence it is discharged into the conveyer F and carried away to any desired point as finished material. The spout 15 c², Figs. 1 and 2, delivers a small percentage of the material, more or less, to the lower section of the granulator, Fig. 6, where the operation is as hereinafter described.

II represents an elevator for the liquid material or material in a fluid or very moist state, and whereby the receiving-tanks K and K' are kept supplied. There are two drying-cylinders shown in plan side by side and a tank for each, so that a single elevator 25 serves for both tanks, and the worm L carries the material over to tank K', or it may flow over by gravity. Delivery-spout k supplies the material to the granulator.

Now referring especially to Figs. 5 and 6 we have what I choose to term a "granulator" and which when analyzed is a combined mixer, disintegrator, and duster—that is, the upper section G of the granulator is used to mix the materials, the lower section has a 30 series of cutting-blades to cut up into bits the lumps of material coming to it, and the spiral blade following in this lower section turns the material around and coats the small lumps or bits with the dust that is fed in through 35 spout c². More or less dry material comes through this spout c² as may be needed for dusting the lumps, and however refractory the material delivered from screen C it will be prepared by the granulator for further 40 handling in the drying-cylinder. In some cases a considerable volume of dry material through spout c² will be needed and in others not so much, the condition of the material as well as other considerations being involved 45 to determine how much is needed from time to time. The same is true in the case of spout c, to which the flow of material is governed by valve c⁴. Conditions of fire and quantity and condition of the raw material have especially 50 to do with the feed through this spout. The feed of raw material through channel k likewise depends on certain conditions, especially that of the fire. The operator of the machine cannot be expected to govern the 55 firing, which may vary considerably during a run; but whatever the fire, whether high or low, the operator can make the most of the fire he has and get uniformity in the product by adapting the quantity of material through 60 both the raw and the partly dry and dry channels to the state of the fire. With a high heat the supply of raw material would be increased 65

and the return stream would be governed to put this greater flow of raw into the right condition for the drier, and so on. But notwithstanding the fact that varying amounts of dry material are diverted with the partially dry through the cylinder the day's output of dry product at last will be equal proportionately to the quantity of wet that has been 70 carried through the machine.

In the casing or pan G of the granulator are two parallel revolving shafts G' and G², each with blades g, which are generally caused to revolve so that the upper ends of the blades 80 will rotate toward each other. These shafts are driven from the main shaft M, which passes through the lower granulator-casing G⁴ and carries blades m, similar to blades g, and also a spiral conveyer-blade m' in its 85 outer end. Upon the shaft M is a pinion m², meshing with gear g' on the shaft G², and by the side of this gear is a pinion g², which meshes with a corresponding pinion g³ on the shaft G', so that both shafts G' and G² are 90 rotated at the same rate of speed, but in different directions, as before indicated.

In the foregoing construction the material is delivered in two streams simultaneously to the granulator, the wet through the spout 95 or pipe k from the tank K and the partly-dried from the hopper C', with a quantity, more or less, as may be needed, of the dry through spout c. Any suitable valve may be employed to regulate the flow of the wet 100 through the pipe k; but the stream flowing through the spout c³ from the screen is continuous and unregulated, except as it may be regulated by the meshes of the screen.

From the granulator the material is delivered to the drying-cylinder by carrier P and discharged into the breeching B. However, in a few instances—such as waste carbonate of lime from pulp, paper, and scrapwork—the wet material may be passed directly into the 110 cylinder without first being mixed with the dry. In such cases the partly-dried material alone passes through the granulator and is treated therein substantially as hereinbefore 115 described.

From the granulator, as above described, the mixed and dusted material is delivered into the drying-cylinder, where it is dried without making any further trouble and without the slightest disposition to adhere to the 120 walls or any part of the machine. Previous to this invention in our efforts to deal with many materials we were unsuccessful, for the reason that the wet material, owing to its 125 sticky nature, would in a short time so fill up the drying-machine that it would be rendered useless.

Sometimes it is desirable to have a screen which will make three or more separations, so that each grade of the coarser material as 130 it is returned to the drier shall pass through separate disintegrators, and this modification is within the scope of the present invention. The finest will be the dry or finished mate-

rial. The next finest may be dry enough for a finished product, so as to be easily pulverized or considerably more moist than the finest, as may be desired, and so on, the percentage of moisture increasing as the separated material increases in size of bits or lumps. In this way the process can be so conducted that the second grade as to size, (next above the finest,) as stated before, may be dry enough to be easily pulverized, and all or practically all of the fine pulverizing would preferably be done when the material was in the second condition, as above described, or the process can be so conducted that the material in the second condition will have dry and moist material mixed, as previously described, as when we want the presence and influence of the moist material.

It is obvious that by separating the material by a screen or by other like means as it comes from the drier into two or more grades as to fineness and by returning to the drier through separate pulverizers a gradual reduction and gradual drying process will be established and that the period of the drying process may be prolonged almost indefinitely, although the period of time occupied by the material in passing through the drying-machine at any one time may be quite short. With many materials this gradual reduction and gradual drying process may be effected quite satisfactorily by separating the dried and partially-dried material as it comes from the drier into two grades as to size and passing the coarser through a disintegrator on its way to the drier and using a disintegrator of such construction and run at such a speed that only a partial reduction takes place each time the material passes through the pulverizer or disintegrator on its way from the discharge to the feeding end of the drying-machine, and as all material which after leaving the machine that does not pass through the screen may be returned to the feed end of the drier again after passing through the pulverizer, all of the material will eventually be pulverized fine enough to pass through the screen, so that by this process the material is gradually dried and gradually pulverized, although using one pulverizer only.

What I claim as new, and desire to secure by Letters Patent, is—

1. The process of drying materials consisting of the following steps: first, passing the material to be dried through a drying-chamber to dry the same, more or less completely; second, sifting or screening out the dried portions; third, reducing the larger undried portions to smaller particles, and fourth, mixing and redrying said undried particles with raw material substantially as described.

2. A drying-cylinder constructed to dry moist material in combination with means to feed said material to the cylinder, a separator to separate the partially-dried product from the dried material, means for conducting the material from said cylinder to said

separator, a granulator for breaking the undried material into smaller particles, means for conducting said undried material from the separator to the granulator, and means for carrying said granulated, undried material from the granulator back to said drying-cylinder, substantially as described.

3. In combination with a drying-cylinder, a sifting device to separate out the dried product, means for carrying the material to said sifter, mechanism for mixing cutting up and dusting a part of the material after it comes from the said sifter, means for carrying the material to said mixing device and means for carrying the material thus treated to the drying-cylinder, substantially as described.

4. In combination with a drying-cylinder and means for feeding said cylinder, a screen for sifting out the dried material, and a granulator, means for carrying the material from the cylinder to the screen and means for conveying a portion of the dried material from the screen to the granulator, and means for discharging the material from the granulator, substantially as described.

5. In a drier the combination with a cylinder of means to feed said cylinder, a mixing-granulator, a screen intermediate the cylinder and granulator to separate the material, means for discharging into the screen and from the screen to the said granulator, a separate receptacle for raw material, means to convey said raw material from said receptacle to the granulator, and means to carry the mixed material from the granulator to said cylinder, substantially as described.

6. In combination with a drying-cylinder, a screen to separate the material to be dried, a granulator to mix, disintegrate and dust said material, means to feed said cylinder, means to carry the material from said cylinder to the screen, separate means to convey the dried and undried material from the separator to the granulator, and means to regulate, control, and separate the flow of said material to the granulator, substantially as described.

7. In a drier a supply-tank for wet material in combination with a granulator or pulverizer made in two sections, means for delivering the material from the said tank to one of said sections, a drying-cylinder, means for carrying the material from said granulator to said cylinder, a separating-screen intermediate said cylinder and granulator, means to convey the material from the cylinder to the screen, means to convey the material from the screen to the granulator-sections, and means for discharging the dried and finished material to any desired point, substantially as described.

8. In a drier of the character described a combined mixer disintegrator and duster composed of two communicating sections, one of said sections provided with a rotating shaft armed with blades for mixing and disintegrating material fed thereto, the other section pro-

vided with a rotating shaft armed with cutters and a spiral blade, in combination with means to actuate said shafts, means to admit undried material to said first section and means for admitting dried material to said second section, receptacles for said dried and undried materials, and means for conveying to and means for discharging said materials from said receptacles into said granulator, whereby the two materials are mixed and disintegrated,

and the wet material dusted with the dried material, and means for separately discharging the dried and undried materials, substantially as described.

Signed by me, at Cleveland, Ohio, this 10th 15
day of March, 1898.

FRANKLIN DAVID CUMMER.
